UNITED STATES PATENT OFFICE.

JACOB C. BARRETT, OF YOUNGSTOWN, OHIO.

BLAST-FURNACE CONSTRUCTION.

943,374.

Specification of Letters Patent. Patented Dec. 14, 1909.

Application filed May 19, 1909. Serial No. 496,942.

To all whom it may concern:

Be it known that I, JACOB C. BARRETT, of Youngstown, Mahoning county, Ohio, have invented a new and useful Blast-Furnace Construction, of which the following is a full, clear, and exact description, reference being had to the accompanying drawings, forming part of this specification, in which—

Figure 1 is a vertical sectional elevation 10 of a portion of a blast furnace constructed and arranged in accordance with my invention; Fig. 2 is a horizontal section on the line II—II of Fig. 1; Fig. 3 is a side elevation showing an improved form of cooling 15 plate forming part of my invention; Fig. 4 is a longitudinal section on the line IV—IV of Fig. 3; Fig. 5 is a top plan view of the cooling plate shown in Figs. 3 and 4; and Fig. 6 is a sectional side elevation showing 20 a modified form of cooling plate constructed in accordance with my invention.

My invention relates to the construction 25 of blast furnaces and the use of water-cooled plates for protecting the refractory lining of such blast furnaces.

The invention more particularly relates to 30 cooling of the refractory lining in the shaft of such furnaces above the furnace mantel plate, and to the construction of the cooling plates used in connection therewith.

The object of my invention is to provide 35 improved means for cooling the shaft of such furnaces, by which the plates are securely held in place in the refractory lining, and by the use of which a much greater cooling effect is presented to the lining with a very great reduction in the number of plates necessary to obtain the desired cooling effect.

Heretofore it has been attempted to cool 40 part of the refractory shaft lining of blast furnaces by placing one or two rows of flat cooling plates at points a short distance above the mantel plate of the construction 45 ordinarily used in the bosh of the furnace. The use of such plates requires that they be placed in rows located vertically above one another in planes a considerable distance from each other. The cooling surface presented by such plates toward the interior of 50 the furnace is comparatively small, and as a result, the lining rapidly becomes burned or worn in irregular lines extending between the rows of such plates. By means of my 55 improved cooling plate, and improved manner of securing these plates in the shaft

lining, a much greater cooling effect is obtained and these difficulties are overcome and prevented.

In the drawings, 2 represents the well, 3 the bosh, and 4 the lower part of the shaft of a blast furnace. The refractory shaft lining 5 is surrounded by the usual metallic furnace shell 6. The shaft lining and the shell are supported on the mantel plate 7, 60 which is carried by column supports 8 in the usual manner. Placed in the refractory lining 5 of the furnace shaft and spaced at suitable intervals, is a series of rows of hollow metal water-cooled plates 9, these plates also 65 forming part of my invention.

As shown in Figs. 3, 4, and 5, a hollow coil is formed by the bent pipe 10, which is cast in place in the surrounding metal plate. The ends of the pipe terminate in the horizontal leg 9^a of the cooling plate, and are 70 connected to suitable water supply or inlet and outlet pipes.

It will be seen by reference to Figs. 3, 4, and 5 that the cooling plate is of peculiar 80 construction, and has a horizontally extending leg 9^a formed integral with the vertically extending leg 9^b. Instead of casting a pile coil in a cast metal body, as is shown in Figs. 3, 4 and 5, the plates may be cast 85 hollow as is shown in Fig. 6. In placing these plates in the furnace when the refractory shaft lining is being constructed, the plates are secured at the proper elevation, and are then surrounded by the refractory 90 lining 5. The vertical legs 9^b present a vertical cooling surface of large area toward the interior of the furnace, and the horizontal leg 9^a serves to securely hold the plate 95 in place in the refractory lining.

In assembling the plates in place in the lining, a suitable number are spaced at regular intervals, so as to encircle the interior of the furnace and the refractory lining is then continued until it reaches such 100 a height that another row of plates is to be put in place. It will be seen that should the refractory material in the shaft lining, extending beyond the inner surface of the vertical legs 9^b of the cooling plates, become 105 burned or worn away by the passage of stock through the furnace, even to an extent to expose the vertical surfaces of the plates, the horizontal legs will still securely hold the plates in place. The plates in being 110 placed in position, are arranged so that the plates in one row are staggered with rela-

tion to those in the adjacent row or rows. The assembling of the plates as described is then carried out with succeeding rows of plates, and the plates may be placed in the lining at suitable intervals to the extreme top of the furnace shaft when desired.

The advantages of my invention will be apparent to those skilled in the art. Instead of having a thin, narrow edge of the water-cooled plate presented for cooling action toward the interior of the furnace, a large surface is presented by each plate and the plates are disposed in such manner in the furnace as to give a much greater cooling effect than has heretofore been found possible with plates of the same weight. The angular or horizontal leg of the cooling plates affords a secure means for supporting and retaining the plates in place in the furnace lining.

The number of plates required to effectively water-cool the shaft of a furnace is very largely reduced, and by reason of the novel securing means employed for the plates, the plates can be placed in rows which are very much closer to each other than has been possible in the constructions used heretofore.

Modifications in the construction and arrangement of the parts may be made without departing from my invention. The relative length of the horizontal and vertical legs may be changed as is desired. The size of the plates and the length compared to the width may be varied, and other changes may be made.

I claim:

1. In a blast furnace, a refractory lining, and a cooling plate embedded in said lining, the cooling plate having cooling surfaces extending at an angle to each other, the opposite walls of the cooling surfaces being in contact with the lining, and connections for circulating a fluid within passages in said plate; substantially as described.

2. In a blast furnace having a refractory lining, a cooling plate having a vertically extending leg formed integral with a horizontally disposed leg, the opposite walls of the vertical and horizontal legs being in contact with the lining, hollow passages in said plate and means for circulating a cooling fluid in said passages; substantially as described.

55 3. In a blast furnace having a refractory

lining, a cooling plate embedded therein having a vertically extending leg formed integral with a horizontally disposed leg, the opposite walls of the vertical and horizontal legs being in contact with the lining, hollow 60 passages in the vertical leg of said plate and means for circulating a cooling fluid in said passages; substantially as described.

4. In a blast furnace, a refractory shaft lining and cooling plates embedded in said 65 lining having integral horizontally and vertically extending water cooled surfaces, the opposite walls of the horizontal and vertical surfaces being in contact with the lining, said plate having hollow passages therein 70 and connections for circulating water through said passages; substantially as described.

5. In a blast furnace, a refractory shaft lining and a plurality of encircling cooling 75 plates embedded in said lining having integral horizontally and vertically extending water cooled surfaces, the opposite walls of the horizontal and vertical surfaces being in contact with the lining, said plates having 80 hollow passages therein and connections for circulating water through said passages; substantially as described.

6. In a blast furnace, a refractory shaft lining and a plurality of encircling cooling 85 plates embedded in said lining having integral horizontally and vertically extending water cooled surfaces, the opposite walls of the horizontal and vertical surfaces being in contact with the lining, said plates having 90 hollow passages therein and connections for circulating water through said passages; substantially as described.

7. In a blast furnace, a refractory shaft lining and a plurality of encircling cooling 95 plates in said lining having integral horizontally and vertically extending water cooled surfaces, said plates having hollow passages therein and connections for circulating water through said passages, the 100 plates in one row being staggered relative to those in an adjoining row; substantially as described.

In testimony whereof, I have hereunto set my hand.

JACOB C. BARRETT.
